UNITED STATES PATENT OFFICE.

JOHN E. OSTLINE, OF LIVERPOOL, ENGLAND, ASSIGNOR, BY MESNE ASSIGNMENTS, TO
AUTOMATIC ELECTRIC INC., OF CHICAGO, ILLINOIS, A CORPORATION OF DELAWARE.

TRAFFIC-RECORDING EQUIPMENT FOR TELEPHONE SYSTEMS.

Application filed April 18, 1924, Serial No. 707,419. Renewed January 9, 1928.

The present invention relates in general to traffic recording equipment for telephone systems, and is particularly concerned with the provision of appropriate equipment at 5 a central point for recording traffic over trunk groups of a multi-office telephone system.

In manual practice, in order to determine the traffic, what is known as the "peg count" 10 method, has been used to some extent. This method consists of the counting of connections set up at regular intervals, and gives a fair idea of traffic loads if carried out consistently. The difficulty in applying this 15 method to automatic connections is the time and labor which is required in counting the connections from either switches or repeaters.

The chief object of the present invention, 20 therefore, is to provide traffic recording equipment which will accurately record the number of busy trunks of a group during a given time.

Another object is to provide equipment 25 for the above purpose, which may be economically manufactured, is entirely automatic in its operation, and which is very flexible in that it can be used in both automatic and manual systems.

Another object is to so design the above 30 apparatus that the actual recording equipment can be placed in a centrally located office and all recording controlled thereat, thereby reducing the labor involved in taking and tabulating the observations to a minimum.

Referring now to the drawings, Figs. 1 to 3, when laid out with Fig. 2 immediately below Fig. 1, and Fig. 3 to the right of 40 Fig. 2, show by means of the usual diagrams sufficient of the circuits and apparatus to enable the invention to be readily understood.

Referring to the drawings more in detail, 45 Figs. 1 and 2 taken together show all of the equipment in the recording office. This equipment mainly consists of a register or recording apparatus R, a digit selecting switch DSS, and an office selecting switch OSS.

The register R consists of a three column 50 motor driven printing type adding machine arranged so that the usual key levers or as many of them as are used, are operated by 55 magnets. A machine which will serve is

the well known Burroughs, in which keys corresponding to the different digits of a number are depressed, followed by the depression of the starting or printing key, whereupon the number corresponding to the 60 depressed keys is printed on a tape. According to the circuit arrangement disclosed herein only the keys in the units and tens 65 columns and the first five hundreds keys are used, in addition to the key for controlling the printing action. As indicated on the drawing, which shows diagrammatically the magnets which operate the keys, the five hundreds keys are used to indicate officers while the tens and units keys indicate the 70 number of connections, providing for recording a maximum of 99 connections in any one of five different offices. As an example, the number 369 appearing on the tape would indicate 69 connections in office No. 3. 75

The switches DSS and OSS are of the usual and well known rotary type commonly used as individual line switches. The switch DSS, however, instead of having double wipers, has two sets of single wipers set at 80 a 180 degree angle, one set engaging its first set of bank contacts as the other set disengages its last set. In this manner a fifty contact switch is obtained.

In addition to the apparatus above described a number of relays, a number of manually operable keys, and a cam 70 are provided. The relays are for various switching operations which will be described hereinafter. The keys comprising keys K' 85 to K^s are office keys and are provided to enable an attendant to disconnect the recording equipment from association with any office when desired. With these keys in normal position, traffic in all the offices is recorded, a record being made first of the traffic in one office, then the next, and so on, until all offices have been tested, when the recording apparatus starts over again with the first office. The cam 70 is constantly 90 rotating at the rate of one rotation per minute and is effective when the key K is in operated position to periodically cause the release of the recording equipment and to cause the office selecting switch OSS to move 95 its wipers into association with the trunk extending to the next office in which traffic is to be recorded.

Fig. 3 shows the counting equipment of one office (all other offices being provided 100

with like equipment), which consists of two counting switches CS and CS'. These switches are mechanically the same as switch DSS of Fig. 1. As will be seen from the drawing, each of these switches has access to the release conductors of fifty trunk lines making a total of one hundred trunks which may be observed in a single office. The purposes of the various relays in this figure 10 will be fully described hereinafter.

In order to enable the invention to be clearly understood, the operation of the system will now be described in detail. For this purpose it will be assumed that the 15 counting equipment shown in Fig. 3 of the drawings is located in the No. 1 office. It will further be assumed that the attendant desires to record the traffic upon the trunk groups of all offices, and that the attendant 20 in the recording office operates the start key at a time when the cam 70 and the wipers 71-74, inclusive, of the office selecting switch OSS are in the position shown in the drawing.

25 When the attendant operates the start key K a circuit is completed which includes slow releasing relay 64 in the recording office and high resistance relay 101 in the No. 1 office. This circuit may be traced from grounded 30 conductor 19, contacts of start key K, armature 67 and its resting contact, springs controlled by armature 58, winding of relay 64, wiper 72, start conductor 20, springs controlled by armature 104, and the winding of 35 high resistance relay 101 to battery.

For the present we will consider only what takes place in office No. 1. Due to the high resistance of relay 101, relay 64 in the recording office does not operate at this time.

40 Relay 101 in office No. 1, however, operates and at its armature 102 completes a circuit for the motor magnet 119 of the counting switch CS. This circuit extends from grounded working contact of armature 102 and the said armature, armature 114 and its 45 resting contact, wiper 121, resting contact of armature 116 and the said armature, armature 109 and its resting contact, armature 117 and its resting contact, and the winding of motor magnet 119 to battery.

The operation of relay 101 also completes a circuit for slow releasing relay 107. This circuit extends from battery, resistance 110, the winding of relay 107, armature 116 and 50 its resting contact, and the grounded wiper 121. During the time motor magnet 119 is at normal, however, relay 107 is short circuited by ground on wiper 121 being extended by way of interrupter springs 120,

55 its resting contact, and the said armature to the resistance 110. As soon as the motor magnet 119 operates this short is removed from relay 107 and this relay operates, at armature 108 closes a point in 60 the count conductor 129 extending back to

the recording office, and at its armature 109 opens a point in the previously described operating circuit of motor magnet 119, causing this magnet to deenergize to advance its wipers 121-124, inclusive, one step. The de- 70 energization of motor magnet 119 causes the short to be again placed around the winding of slow relay 107. As soon as this latter relay deenergizes a new circuit is completed for the motor magnet 119 which extends 75 from the grounded multiplied bank contacts 130, wiper 121, resting contact of armature 116 and the said armature, armature 109 and its resting contact, armature 117 and its resting contact, and the winding of motor 80 magnet 119 to battery. The operation of motor magnet 119 again causes the short to be removed from slow relay 107, permitting this relay to be again energized to open the circuit of the motor magnet. This alter- 85 nate operation of motor magnet 119 and slow relay 107 continues until the wipers 121-124, inclusive, have completed a complete revolution, the wiper 122 being substituted for the wiper 121 when the switch 90 takes its twenty-fifth step. The switch CS upon taking its forty-ninth step positions its wiper 122 on contact 131 which, instead of being connected to direct ground, supplies ground through the winding of low 95 resistance relay 105. Motor magnet 119 operates as before and relay 105 also operates. Relay 105, upon operating, at its armature 106 completes a circuit for the lower winding of relay 111. Relay 111 only operates 100 its armature 114 when its lower winding alone is energized. This armature, upon operating, breaks a point in the original 105 operating circuit of magnet 119 and completes a shunt about the upper winding of relay 111. As soon as magnet 119 is fully 110 operated relay 107 again operates and breaks the operating circuit of relay 105 and magnet 119. Relay 105 deenergizes thereby removing ground from the lower 115 terminal of the upper winding of relay 111. Current now flows through both windings of relay 111 and this relay now operates its armatures 112, 113 and 115 to 117, inclusive. At armature 113 a circuit is prepared for 120 relay 103, and at armatures 115 to 117 and their working contacts switch CS' is substituted for switch CS. The deenergization of magnet 119 causes the wipers of switch CS to be moved another step into their 125 initial starting position. Upon the deenergization of relay 107, since relay 111 is now operated, a circuit is completed for motor magnet 118 of the switch CS'. This circuit may be traced from battery, winding 130 of the motor magnet 118, working contact of armature 117 and the said armature, resting contact of armature 109 and the said armature, armature 116 and its working contact, wiper 125 and its first bank con-

tact, working contact of armature 114 and for the digit selecting switch DSS, from the said armature, and armature 102 and its working contact to ground. The motor magnet 118, upon energizing, removes a short from slow relay 107 in the same manner as did motor magnet 119. The relay 107 and motor magnet 118 now operate alternately in the same manner as previously explained with reference to the switch CS, 5 until the switch CS' has completed a complete cycle of operation. Since the relay 111 is already energized, when wiper 126 takes its forty-ninth step the relay 105 again operates, this time in series with magnet 118 and, since armature 113 is in operated position, causes the operation of relay 103. Relay 103, upon operating, substitutes its low resistance locking winding for the high resistance relay 101. Relay 101 deenergizes 10 and in so doing breaks the locking circuit of relay 111. This latter relay accordingly restores to normal. All equipment at the No. 1 office is now in its original position with the exception of relay 103. The substitution 15 of low wound relay 103 for relay 101 causes the current flow in the conductor 20 and in the relay 64 (Fig. 2) to be materially increased for a purpose which will subsequently be pointed out.

As previously pointed out, the conductors extending from the bank contacts traversed by wipers 123, 124, 127 and 128 extend to release trunk conductors of the trunk group upon which traffic is to be recorded, or, if 20 manual trunks are being observed, to conductors of such trunks adapted to be grounded when taken for use.

Since, as previously stated, each of the fifty bank contacts of switch CS and CS' 25 are connected to the release trunk conductor of a different trunk, it follows that wipers 123 and 124 in travelling over their respective bank contacts, upon engaging grounded or busy release trunks, cause impulses to be transmitted back over conductor 132, resting contact of armature 112 and the said armature, armature 108 and its working contact to count conductor 129 extending to the recording equipment at the centralized 30 office, wiper 73 (Fig. 2), and the winding of pulsing relay 51 to battery. As previously explained, the various conductors of the switch CS' are substituted for those of CS when the relay 111 is operated, and therefore the wipers 127 and 128 in rotating and upon engaging grounded contacts cause impulses to be sent out over conductor 133, working contact of armature 112 and the said armature, over the previously described 35 circuit to the pulsing relay 51.

We will now turn our attention to what takes place in the recording office responsive to the impulses transmitted over conductor 129 to pulsing relay 51. Each time the pulsing relay 51 operates a circuit is completed

for the digit selecting switch DSS, from the grounded start conductor 19, springs of the start key K, in operated position, working contact of armature 53 and the said armature, conductor 38, and the winding of motor magnet 10 to battery, causing the switch DSS to move its wipers 11-16, inclusive, one step. The switch DSS, upon completing its initial step, at its wiper 15 opens a point in the operating circuit of switching relay 18, and at this same wiper and its second bank contact completes a circuit for relay 52. This circuit may be traced from battery, winding of motor magnet 10, conductor 38, interrupter springs 23, conductor 24, wiper 15, conductor 25, conductor 37, springs controlled by armature 55, winding of relay 52, conductor 39, resting contact of armature 68 and the said armature, springs of key K to the grounded conductor 19. Relay 52 operates, at its armature 54 closes a point in the operating circuit of switching relay 18, and locks itself up over a circuit including both its windings and its armature 55 in series. It will be seen that since the operating circuit of relay 18 must include wiper 15 and its first contact this relay cannot become energized unless the wiper 15 is moved fifty steps.

The reason for the above arrangement will be quite evident after a slight study of the connections extending to the operating magnets of register R via contacts of relay 18, i. e., it will be seen that the operation of any combination of magnets to register numbers from one to forty-nine may be accomplished without the operation of relay 18, but if any number greater than 49 is to be registered relay 18 must be operated. For the purpose of illustration it will be assumed that, during the operation of switches CS and CS', fifty-five busy (grounded) trunks are engaged and, consequently, the motor magnet 10 causes the switch DSS to take fifty-five steps. When switch DSS takes its fiftieth step wiper 15 is again positioned on its first contact and since relay 52 is now in an operated condition a circuit is completed for switching relay 18. This circuit extends from battery, winding of magnet 10, interrupter springs 23, conductor 24, wiper 15, conductor 42, resting contact of armature 57 and the said armature, armature 54 and its working contact, conductor 41 and the upper winding of relay 18 to ground. Relay 18, upon operating, locks itself up over a circuit extending from battery, lower winding of said relay, working contact and upper armature of said relay, conductor 39, resting contact of armature 68 and the said armature, conductor 29, and contacts of key K to grounded conductor 19. Relay 18 upon operating the remainder of its armatures disconnects certain of the magnets of register R, used only when digits of less than

fifty are to be registered, and connects up certain of the magnets, used only when digits of fifty or over are to be registered.

It was hereinbefore pointed out that when switches CS and CS' have each completed a cycle of operation that the current flow through relay 64 is increased by the substitution of the low winding of relay 103 for the high winding of relay 101. Relay 64 therefore operates, at its armature 63 completes a circuit for slow-relay 60, and at its armature 65 applies ground potential to conductor 43. The grounding of conductor 43 causes circuits to be completed for the office register magnet 1 and certain of the number recording magnets of the register R. The circuit for the office magnet may be traced from grounded conductor 43, branch conductor 35, wiper 74 of the office selecting switch OSS, conductor 48, and the winding of office magnet 1 to battery.

Since it has been assumed that fifty-five trunks were busy in the office No. 1, during this particular recording period, the tens and units magnets 5 and 5, respectively, of the register R, will be the ones operated. The circuit for tens magnet 5 may be traced from the grounded conductor 43, branch conductor 31, wiper 11 now standing on its fifth bank contact, conductor 22, armature 27 and its working contact, conductor 28 and the winding of the tens magnet 5 to battery. The circuit for the units magnet 5 may be traced from the grounded conductor 43, branch conductor 33, wiper 13, now standing on its fifth bank contact, conductor 26, and the winding of units magnet 5 to battery. As previously pointed out, at the same time that ground was applied to conductor 43 a circuit was also completed for slow release relay 60. This latter relay, upon operating, at its armature 62 closes a point in the operating circuit of the register control magnet X of the register R, and at its armature 61 completes a circuit for relay 56. Relay 56, upon operating, at its armature 57 opens a point in the initial circuit of switching relay 18, and at its armature 58 locks itself up by way of the resting contact and armature 67 of relay 66. Relay 56 also, at its armature 59 closes a point in a restoring circuit for the switch DSS, and at its armature 60 opens the energizing circuit of slow release relay 64 and relay 103. This latter relay, which is located in the No. 1 office, deenergizes, again connecting the relay 101 to the start conductor 20. Relay 64, upon restoring, at its armature 65 removes ground from conductor 43, but this in no way affects the operated armatures of magnets of the register R since these armatures are mechanically locked in operated position until registration has taken place. Relay 64, upon retracting its

armature 63, opens the circuit of slow release relay 60, and at the back contact of the armature 63 completes a circuit for the motor start relay of the register R. This circuit may be traced from grounded conductor 29, armature 63 and its resting contact, working contact of armature 62 and the said armature, conductor 40, and the winding of motor start relay to battery. This circuit is opened a moment later when relay 60 retracts its armatures. The construction of the register R is such that the armature of the register control magnet X and the armatures of the magnets are locked up when operated and are not unlocked until the motor of the register has caused the registering operation to be completed at which time the unlocking of the armature of the register control magnet takes place. It will therefore be seen that the opening of the circuit of this magnet in no way affects the registering operation. Relay 60, upon retracting its armature 61, completes a circuit for restoring switch DSS to normal. This circuit may be traced from grounded conductor 29, armature 61 and its resting contact, working contact of armature 59 and the said armature, conductor 37, to the multipled bank contacts associated with wipers 15 and 16, in the present case by way of wiper 15, conductor 24, interrupter springs 23, and the winding of motor magnet 10 to battery. Since this circuit includes the interrupter springs of motor magnet 10, it will be evident that this magnet will operate its armature in the manner of a buzzer and, in so doing, move wipers 11-16, inclusive, around until they are in the position shown in the drawing. In this position, since the wiper 16 is not on any of its bank contacts, and further since the wiper 15 is positioned on an ungrounded bank contact, no further operation of the switch DSS occurs until this switch is again started by the counting relay 51 in the manner previously described.

At this stage of the operation, all equipment at the recording office is at normal with the exception of switching relay 18, relay 52, and relay 56, these relays being still held up by current supplied through armatures 67 and 68 of slow release relay 66. As soon as the time interval of one minute elapses cam 70 momentarily operates its spring 30, thereby momentarily completing a circuit for slow release relay 66 and motor magnet 69 in multiple. Relay 66, upon operating, at its armatures 68 and 67 breaks the previously described holding circuit of relays 18, 52 and 56, and these relays accordingly restore to normal. Relay 66 also, at its armature 67 and its working contact, applies ground to private conductor 37 of switch DSS, as soon as relay 56 restores its armature 59, but this has no effect at this time as this switch is already at normal. Magnet 69, upon ener-

gizing and again deenergizing, moves its wipers 71-74, inclusive, into engagement with their second bank contacts with which are associated the conductors extending to office No. 2 and the conductor extending to the office magnet 2 of the register R. Relay 66, upon restoring, now completes a circuit for the slow acting relay 64 and the relay 101 of the second office to be observed.

10 This circuit extends from the grounded conductor 29, armature 67 and its resting contact, through springs controlled by armature 58, winding of relay 64, wiper 72, now positioned on its second contact, and the 15 start conductor 20' to the relay 101 located in the second office. The operations which take place in the second office and in the recording office from now on will be similar to those hereinbefore described and 20 therefore need not be repeated.

After a registration has been made in each of the five offices the wiper 71 is stepped on to the sixth contact, and since this and the remaining contacts in the bank are grounded 25 the switch OSS will automatically rotate until wiper 71 is again positioned on its first bank contact. If, in the meantime, none of the keys, K¹-K⁶, inclusive, have been operated traffic conditions in offices 1-5, inclusive, will be again recorded at one minute 30 intervals in sequence as before, but if any of the keys have been operated, the corresponding bank contact associated with wiper 71 will be grounded, and when the wiper 71 reaches such bank contact registration in 35 that office will be omitted.

When it is desired that registration of all offices be discontinued the attendant restores start key K to normal. The restoration of 40 this key causes ground to be removed from conductor 29, thereby opening the circuit of any of the relays 18, 52, or 56, which may be operated at this time. The restoration of key K also grounds conductor 37. The 45 ground on this conductor will cause the switch DSS to restore to normal in the same manner previously described. The switch OSS has no normal position and therefore its wipers remain on the contacts associated 50 with conductors extending to the particular office which is being observed at the time the start key is restored, unless the wiper 71 happens to be on one of the bank contacts not utilized, which, as will be seen, is permanently grounded, and in this case the 55 switch OSS will automatically rotate until the wiper 71 comes into engagement with the first bank contact with which an observed office is associated.

60 While the present system has been described as only having five offices, it will be evident to those skilled in the art that, without increasing the equipment at the recording office, trunk groups from twenty-five 65 offices may be handled.

In the preceding description it was assumed that the start key K was operated just after the cam 70 had operated spring 30. A brief description will now be given of the operations which take place should the key K be operated when the cam 70 is at some other position. Under these conditions the operations take place as previously described except that, if switches CS and CS' fail to have completed their cycle of operation, which may often be the case, when spring 30 is grounded, relay 64 will not be energized and, therefore, conductor 43 will not be grounded and no partial registration will take place. Relay 66, upon operating, at its armature 67 and its working contact extends ground via resting contact of armature 59 and the said armature to private conductor 37 to restore switch DSS to normal. When ground is removed from spring 30 magnet 69 restores and in so doing moves its associated wipers into connection with the next contact set. Relay 66, upon retracting its armatures, connects the relay 64 in series with the relay 101 of the office selected by switch OSS, and the recording equipment is now in readiness to make a complete record of the traffic conditions in the trunk group of the selected office.

Having fully described the invention, what is considered new and is desired to have protected by Letters Patent will be pointed out in the appended claims.

What is claimed is:

1. In a telephone system, groups of trunk lines, means for making said trunk lines busy, means individual to each group for periodically testing the busy or idle condition of all trunks in the associated group in a definite order, and automatic means common to all the said groups for recording the number of the particular group and the number of trunks busy in such group in each instance.

2. In a telephone system, a main office, a branch office, a trunk line connecting said offices, a group of trunk lines in the branch office, means for making said trunk lines busy, means in the branch office for testing the idle or busy condition of said trunk lines, means at the main office controlled by said testing means to register the number of trunks found busy, a recording device at the main office for recording the number set up on said register device, and a relay associated with said testing means operated only when all said trunks have been tested for causing the operation of said recording device.

3. In a telephone system, a main office and a plurality of branch offices, a trunk line extending from each branch office to said main office, a plurality of trunks at each branch office for use in inter-connecting calling and

called subscribers' lines, traffic recording equipment at the main office, means associated with said recording equipment automatically operated to connect any branch office therewith for a predetermined interval, testing apparatus at such branch office for determining the number of trunks that are in use at one time, means at the main office for initiating the operation of said testing apparatus, means in said testing apparatus for transmitting an impulse of current to the recording apparatus each time a busy trunk is found, and means in said testing apparatus automatically operated when all trunks associated therewith have been tested for causing a record to be printed at the recording office.

4. In a traffic recorder, a plurality of trunk or line testing devices, a common registering device, a testing device selector for connecting said registering device with said testing devices successively, and a recording device controlled by said registering device each time the same is connected to a testing device.

5. In a traffic recorder, a plurality of trunk or line testing devices, each comprising means for testing a group of trunks or lines, a registering device, and means for connecting said registering device to said testing devices successively.

6. In a traffic recorder, a plurality of trunk or line testing devices, each comprising means for testing a group of trunks or lines, a registering device, means for connecting said registering device to said testing devices successively, and means for automatically starting each testing device responsive to its being connected with by said registering device.

7. In a traffic recorder, a plurality of trunk or line testing devices, each comprising means for testing a group of trunks or lines, a registering device, means for connecting said registering device to said testing devices successively, means for automatically starting each testing device responsive to its being connected with by said registering device, and means in each testing device for setting said registering device.

8. In a traffic recorder, a plurality of trunk or line testing devices, each comprising means for testing a group of trunks or lines, a registering device, means for connecting said registering device to said testing devices successively, means for automatically starting each testing device responsive to its being connected with by said registering device, means in each testing device for setting said registering device, means for restoring the registering device each time before it is connected with a different testing device, and a recording device controlled by said registering device.

9. In a telephone system, groups of trunk lines located in different telephone offices,

testing equipment in each office for determining the busy or idle condition of the trunk lines therein, a common recording point, means for successively connecting said common recording point with each of said testing devices, and means at said common recording point for skipping any testing equipment in any of said offices at will. 70

10. In a telephone system, groups of trunk lines located in different telephone offices, testing equipment in each office for determining the busy or idle condition of the trunk lines therein, a common recording point, means for successively connecting said common recording point with each of said testing devices, means at said common recording point for starting the testing equipment in said offices when connected with and for recording the traffic conditions of the groups of trunk lines in said offices, and 80 means at said common recording point for skipping the testing of any of said groups of trunk lines in said offices at will. 75

11. In a telephone system, groups of trunk lines located in different telephone offices, testing equipment in each office for determining the busy or idle condition of the trunk lines therein, a plurality of supervising trunk lines connecting said offices, respectively, with a common recording point, and means at said common recording point for starting the testing equipment in said offices and for recording the traffic conditions in the various groups of said trunk lines by means of control from said testing equipment exercised over said supervising trunk lines. 90 95

12. A traffic recorder, for use in recording the busy or idle conditions of lines in a telephone system, comprising means for automatically testing said lines, a printing device controlled by said testing means, and means for periodically repeating said test automatically. 105

13. In a telephone system, means for testing telephone lines and for automatically making each time a permanent record indicating the busy conditions of the lines tested, and means for automatically repeating said tests periodically. 110

14. In a traffic recording system for recording traffic in group telephone lines, means for testing each of said lines and for recording the busy condition of the tested lines, and means for preventing the testing 120 of any group or groups of lines while permitting the preceding group or groups of lines to be tested.

15. In a traffic recorder for recording traffic conditions in grouped telephone lines, means for testing said groups of lines successively, and means automatically effective between the testing of successive groups for recording the number of one of the groups. 125

16. In a traffic recorder for recording 130

- traffic conditions in grouped telephone lines, means for testing said groups of lines successively, and means automatically effective between the testing of successive groups for 5 recording the number of one of the groups and for recording the number of lines that were busy in the last tested group.
17. In an apparatus for testing the condition of each of a number of conductors, 10 means effective when the apparatus has been started for maintaining said apparatus in operation until all of the conductors have been tested and for then stopping the apparatus, and means for periodically restarting the apparatus.
18. In an apparatus for testing the condition of each of a number of conductors, 15 means effective when the apparatus has been started for maintaining said apparatus in operation until all of the conductors have been tested and for then stopping the apparatus, and means for periodically restarting the apparatus, the interval between starting periods being substantially greater than 20 the testing period.
19. In a telephone system, groups of trunk lines, means for periodically determining the busy or idle condition of all of the trunks in each group in a definite group and trunk or- 25
- der, and means for making two indications 30 one of which indicates the group tested and the other of which indicates the condition of the trunks of the groups.
20. In a telephone system, groups of trunk lines located in different telephone offices, 35 testing equipment in each office for determining the busy or idle condition of the trunk lines therein, supervisory trunk lines connecting said offices respectively with a common supervising point, and means at said 40 common supervising point for starting the testing equipment in said offices and for indicating the traffic condition in the various groups of said trunk lines by means of control from said testing equipment exercised 45 over said supervisory trunk lines.
21. In an apparatus for testing the traffic conditions in grouped telephone lines, means for testing each of said lines in a definite group and line order, and means for preventing the testing of any group or groups of lines while permitting the preceding group or groups of lines to be tested.

In witness whereof, I hereunto subscribe my name this 27th day of March, A. D., 55 1924.

JOHN E. OSTLINE.
